UNITED STATES PATENT OFFICE.

CHARLES A. SULLIVAN, OF WINDSOR, CANADA, ASSIGNOR OF ONE-HALF
TO EDWARD J. WOODISON, OF DETROIT, MICHIGAN.

REGULATING-VALVE FOR LUBRICATORS.

SPECIFICATION forming part of Letters Patent No. 761,425, dated May 31, 1904.

Application filed July 11, 1902. Serial No. 115,128. (No model.)

To all whom it may concern:

Be it known that I, CHARLES A. SULLIVAN, a citizen of the United States, residing at Windsor, county of Essex, Province of Ontario, Canada, have invented a certain new and useful Improvement in Regulating-Valves for Lubricators; and I declare the following to be a full, clear, and exact description of the invention, such as will enable others skilled in the art to which it pertains to make and use the same, reference being had to the accompanying drawings, which form a part of this specification.

This invention relates to lubricators, and has for its object an improved valve attachment arranged to control the passage through which the oil escapes from the oil-cup of the lubricator into the sight-feed glass. In the operation of this invention the valve is closed when the steam is throttled and is open only when steam is free to pass through the cut-off at the throttle-valve of the engine.

In the drawings, Figure 1 shows a lubricator with the valve-actuator attachment. Fig. 2 is a vertical section through the attachment.

15 A indicates the oil-cup of a lubricator, of which 1 indicates the sight-feed glass, connected to the oil-cup by a fitting 2, through which there is a passage for the flow of oil 20 from the cup into the sight-feed glass. This passage is controlled by a needle-valve 2^a, whose stem is arranged to be actuated by the device embodying this invention in either of the ways hereinafter described.

35 In Fig. 2 the stem 3 of the needle-valve 2^a is provided with a thread 2^b and is inserted through a threaded sleeve 7, which is secured in any suitable way to a diaphragm 8, that divides a chamber 4. The upper part of the 40 chamber 4 is arranged to receive steam through a steam-inlet 5 from steam-pipe 5^a, into which steam is admitted when the throttle 5^b is turned to admit the steam to the engine. The casing of the chamber 4 is secured to the fitting 2 by a two-part coupling-nut 6, that screws onto the fitting 2 and onto which a nipple of the casing screws. The sleeve 7 is concentric with the coupling 6 and with the nipple 6^a, and provision is made that it may

have a motion longitudinal of its axis through 50 the walls of the chamber and through the coupling 6. The stem 3 of the valve 2^a projects through the diaphragm 8, and below the diaphragm 8 it is surrounded by an adjusting-spring 9, that is seated in a nipple 9^a, 55 that forms part of the casing of the chamber 4. The lower end of the nipple 9^a is closed by a perforated adjusting-nut that is externally screw-threaded to engage in internal threads of the nipple 9^a and is internally 60 threaded to engage with the external threads of a stop-sleeve 10. The hollow nut 11 bears against the lower end of the spring 9 and is employed to adjust the tension of the spring 9, the upper end of which bears against the 65 lower face of the diaphragm 8 or, as shown in the drawings, against the lower face of a nut by which the diaphragm 8 is held to the sleeve 7. The spring 9 coacts with the diaphragm to drive the valve 2^a to its seat, from 70 which it is forced by steam-pressure acting against the upper face of the diaphragm 8. The sleeve 10 is adjustable through the nut 11 and is arranged to regulate the amount of opening possible for the valve. The valve 75 and its stem are actuated by the diaphragm, which engages with the stem through the intermediate part or sleeve 7, and the stem 3 can be adjusted in the sleeve 7 by turning the stem on its own axis, and thereby running the 80 threaded part 2^b of the stem along the threaded part of the sleeve.

What I claim is—

1. In combination with a lubricator, a detachable valve-actuator, having in combination a casing provided with means to attach it to the lubricator, a diaphragm spanning the casing, a valve projecting from the casing, a valve-stem therefor passing through the casing and through the diaphragm, a sleeve secured to the diaphragm embracing the valve-stem and adjustably secured thereto, a second sleeve also embracing the valve-stem and passing through a threaded nipple, a threaded nipple engaging a threaded opening in the 90 casing embracing the second-named sleeve on the valve-stem and adjustably secured to said sleeve, a spring surrounding the valve-stem, 95

engaging against the diaphragm and against the threaded nipple, and means for admitting actuating fluid into the casing on the side of the diaphragm opposite said spring, substantially as described.

2. In combination with a lubricator, a detachable valve-actuator having in combination a casing provided with means to attach it to the lubricator, a valve projecting from the

10 casing, a diaphragm spanning the casing, a valve-stem therefor provided with a threaded part and passing entirely through the casing and through the diaphragm, a threaded sleeve secured to the diaphragm embracing the

15 valve-stem and with its threaded part engaging the threaded part of the valve-stem, a second sleeve also embracing the valve-stem, a threaded nipple engaging a threaded opening in the casing, engaging around the second- 50

20 named sleeve on the valve-stem and adjustably secured thereto, a spring engaging against the diaphragm, and means for admitting actuating fluid into the casing on the side of the diaphragm opposite said spring, substantially 55

25 as described.

3. In combination with a lubricator, a detachable valve-actuator, having in combination a casing provided with means to attach it to the lubricator, and with means for the ad- 60

30 mission of actuating fluid, a diaphragm spanning the casing, a valve external to said casing, a valve-stem therefor passing through the attaching means through the casing and through the diaphragm, a sleeve secured to 65

35 the diaphragm and having a reciprocatory motion through the casing and through said attaching means, means for adjustably securing the sleeve to the valve-stem, a second sleeve secured to a wall of the casing and engaging 70

40 around the valve-stem, means for adjusting said second sleeve with respect to the wall of the casing, and a spring engaging against the diaphragm, substantially as described.

4. In combination with a lubricator, a de- 45 tachable valve-actuator, having in combination a casing, means for attaching the casing to the lubricator, a diaphragm spanning the casing, a valve external to the casing, a valve- 75

stem therefor passing through the diaphragm

and through the casing at both sides of the dia- 50 phragm, a reciprocatory sleeve secured to the diaphragm embracing the valve-stem and adjustably secured thereto and having a reciprocatory motion through the casing, a second sleeve on the opposite side of the diaphragm 55 from the first-mentioned sleeve, arranged to guide but allow free reciprocation of the valve-stem therethrough, means for adjusting said sleeve with respect to the diaphragm, a spring arranged to bear against the diaphragm, and 60 means for adjusting the tension of said spring, substantially as described.

5. In combination with a lubricator, a detachable valve-actuator having in combination a casing provided with means for attaching it 65 to the lubricator, and with means for admitting actuating fluid thereinto, a diaphragm spanning said casing, a sleeve secured to said diaphragm reciprocating through said casing and through the attaching means, a valve actuated by said sleeve, a spring reinforcing said diaphragm, concentrically - arranged means for independently adjusting from outside the casing the relation between the valve and the diaphragm and the relation between the dia- 70 phragm and the reinforcing-spring and the vibratory limits of said diaphragm, substantially as described.

6. In combination with a lubricator, a cas- 75 ing provided with a fluid-inlet at one side thereof, a diaphragm secured in said casing, a sleeve secured to the diaphragm, sliding through and guided by a portion of said cas- 80 ing, a spring bearing against the diaphragm, a nut adjustably secured to the casing and bearing against the spring, an independently- 85 adjustable stop for the diaphragm carried by said nut, a valve-stem projecting through said stop and in threaded engagement with the sleeve on the diaphragm, and means on the 90 outer end of said stem for turning the same, substantially as described.

In testimony whereof I sign this specification in the presence of two witnesses.

CHARLES A. SULLIVAN.
